UNITED STATES PATENT OFFICE.

EDMUND SCHULZE, OF LYONS, NEBRASKA.

HAY-STACKER.

No. 853,649.

Specification of Letters Patent.

Patented May 14, 1907.

Application filed January 30, 1907. Serial No. 354,893.

To all whom it may concern:

Be it known that I, EDMUND SCHULZE, a citizen of the United States, residing at Lyons, in the county of Burt and State of Nebraska, have invented certain new and useful Improvements in Hay-Stackers, of which the following is a specification.

This invention relates to hay stackers of that class which are equipped with a movable platform, sometimes known as the stacker-fork, and which are used in connection with drag rakes whereby the load that is to be elevated and deposited upon the stack is conveyed to the stacker and placed upon the stacker-fork while the latter is lowered to a receiving position.

The object of the present invention is to furnish an appliance, known as a retaining device, adapted to be secured upon the teeth of the stacker-fork, for the purpose of retaining the load upon the latter while the rake is being backed away from the latter.

A further object of the invention is to provide a retaining device which, while it will efficiently fulfil the function of retaining the load upon the stacker-fork, will in no wise hinder or interfere with the discharge of the load upon the latter.

Further objects of the invention are to simplify and improve the construction and operation of this class of devices, and to provide an attachment which may be readily, and at small expense, applied to stacker-forks of ordinary construction.

With these and other ends in view, which will readily appear as the nature of the invention is better understood, the same consists in the improved construction and novel arrangement of parts which will be hereinafter fully described, and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawings—Figure 1 is a perspective view of a stacker-fork of conventional construction, equipped with the improved retaining devices. Fig. 2 is a longitudinal sectional view taken through one of the teeth of the stacker-fork. Fig. 3 is a sectional elevation showing a stacker-fork in load receiving

position, and showing also a drag rake which is being backed off after delivering or depositing a load upon the fork. Fig. 4 is a side elevation, partly in section, of the improved retaining device.

Corresponding parts in the several figures are denoted by like characters of reference.

A in the drawings designates a stacker head of ordinary construction, the same comprising the cross-bars 1, 1, teeth 2, 2, and upright guard bars 3, 3; the head is carried by the frame bars 4—4, which are a part of the stacker mechanism.

The improved retaining device consists of an inclined rod or bar 5, preferably made of round iron, the same being provided at its front end with a flat base portion 6 having a countersink aperture 7 for the reception of a fastening member, such as a bolt or screw 8, whereby it may be secured upon one of the teeth 2, near the forward extremity of the latter. The rod 5 is inclined upwardly and rearwardly and it is provided with a foot member 9 which is curved downwardly and forwardly beneath the body of the rod 5, and which terminates in a rearwardly-extending flattened base piece 10 having a countersunk aperture 11 for the passage of a fastening member 12. That portion of the body 5 which extends rearward of the foot piece 9 is curved downwardly, as shown at 13, and it terminates in a moderately sharp point 14.

It is preferred to provide the teeth of the stacker head with recesses, as shown at 15 in Fig. 2, for the reception of the flattened base portions 6 and 10 of the retaining attachment, in order that the upper surface of the teeth may be left smooth, thus avoiding liability of the movement of the hay onto or off the stacker head being obstructed.

The improved retaining attachment may be constructed at small expense, by casting of malleable iron or other suitable material; or it may be constructed, by forging, of wrought iron or steel in an efficient and inexpensive manner.

In practice it is preferred to mount one of the improved retaining devices upon each tooth of the stacker head, as will be seen in Fig. 1 of the drawings; but this is not essential, and one or more of the teeth may, if desired, be left free from the retaining devices.

The operation and advantages of the invention will be readily understood from the

foregoing description taken in connection with the accompanying drawings. When the stacker head is in the load-receiving position, indicated in Fig. 3 of the drawings, 5 a load of hay may be deposited thereon in the usual manner by a drag-rake of ordinary construction; a rake of this character being conventionally shown at R in Fig. 3 of the drawings. When the rake is being withdrawn, 10 the load will be engaged by the retaining devices, the points 14 of which will enter into and engage the load if the latter exhibits a tendency to slide off the stacker head; and said points being slightly down- 15 turned will cause a portion of the load to pack in the spaces beneath the rear ends of the body portions 5 and in rear of the foot portions 9 of the retaining devices, thus causing the load to become firmly gripped 20 and held against further movement while the rake is being backed away from the stacker. When the stacker-fork is manipulated to elevate the load, it is tilted in the usual manner, and the load will be discharged over the 25 guard members 3, as is well understood; the retaining devices will thus in no wise hinder or obstruct the discharge of the load.

~~The improved retaining devices of the present invention are simple, inexpensive, 30 and thoroughly efficient for the purposes for which they are provided; and they may be,~~

at a trifling expense, applied to the heads of stackers of ordinary construction and in present use.

What is claimed is:—

1. A retaining device for hay stackers consisting of a rod supported upon a tooth of a stacker head in an upwardly and rearwardly inclined position and having a terminal downturned point and a forwardly curved 40 foot or supporting member set forwardly beneath the body of the retaining member.

2. A load retaining device for hay stackers consisting of a rod supported upon a tooth of a stacker head in an upwardly and rearwardly inclined position and having a flattened apertured base member at its front end, said rod having a terminal downturned point at its rear end and a forwardly-curved 45 foot set forwardly beneath the body of the 50 retaining device and having a flattened apertured base plate.

3. A load retaining device for hay stackers comprising a body and a foot member converging in a rearward extending terminal 55 point, and having apertured base plates.

In testimony whereof I affix my signature, in presence of two witnesses.

EDMUND SCHULZE.
